RECEIVER SIGHT

Frederick A. Kuhn, Meriden, Conn.

Application January 10, 1938, Serial No. 184,198

2 Claims. (Cl. 33—56)

My invention relates to a gun sight and more especially to a rear or receiver sight for a rifle.

It is well known in the art that the best results from a rear sight, of the aperture or "peep" type, are obtained when the sight is positioned on a rifle with the aperture or "peep" as close to the shooter's eye as possible. As a result, there came to use at an early date a form of sight known as a tang sight, which was mounted on the upper tang of a rifle at the small of the stock. Tang sights are not suitable for use on bolt action rifles, owing not only to the fact that such rifles do not have tangs but also to the fact that a tang sight would interfere with the rearward movement of the bolt. For this type of rifle there has been developed a form of sight which is attached to the receiver of the rifle, usually at that portion rearwardly of the magazine or loading opening known as the bridge. By reason of the fact that the bolt head and cocking piece of the usual bolt action rifle extend rearwardly of the bridge a considerable distance, it will be apparent that the usual receiver sight, when mounted on the bridge, is spaced forwardly a considerable distance from the shooter's eye.

One of the principal objects of the present invention is to bring about a form of sight which may be suitable for attachment directly to the receiver of a rifle, especially a bolt action rifle, and in which the sighting aperture is carried in a position closely adjacent the shooter's eye.

A further object of the invention is to bring about a form of receiver sight of the above character, in which the sighting aperture is in the same general location as the aperture of a tang sight, but which will not interfere with the operation of the bolt of a bolt action rifle.

Bolt action rifles of standardized manufacture are of the same length from the action to the butt plate, and as these are used by shooters of different physical characteristics it will be apparent that the position of the shooter's head on the comb of the rifle stock, when the shooter is holding the rifle in a normal comfortable position, will vary from shooter to shooter. When the rear sight is likewise standardized, both as to form and position on the rifle, it will be apparent that the distance, from the sighting disc or aperture of the sight of the shooter's eye, will vary in accordance with this position of the shooter's head on the rifle stock. Again, it has been found that the normal position of the head on the stock of a rifle varies in accordance with the shooting position. Thus the head and the eye are much closer to

the aperture of the sight in prone position than in off-hand position.

Another object of the invention is to bring about a form of sight in which the position of the "peep" or aperture may be adjusted or varied longitudinally of the rifle, so that the position thereof may suit the individual needs of a shooter, either as to his physical characteristics or as to the particular position adopted.

In carrying out the invention I propose to mount the improved sight on the receiver of a rifle and to extend the aperture supporting part thereof rearwardly from the receiver, into a position closely adjacent the eye of the shooter, and a further object of the invention is to bring about a form of sight, having the above characteristics, in which the principal parts thereof may be readily detached, in order that the sight may not interfere with the use of a telescope sight, and for other purposes.

A feature of the invention resides in an arrangement wherein the aperture and associated parts of the sight may be readily detached from and reassembled on the rifle, without requiring the readjustment thereof into sighting position.

Further features of the invention reside in improved constructional details which bring about greater ease and accuracy in the adjustment of the sight into sighting position.

To these and other ends, the invention consists in the novel features and combinations of parts to be hereinafter described and claimed.

In the drawings,

Fig. 1 is a perspective side elevational view of a rifle having a sight in accordance to the invention attached thereto;

Fig. 2 is a plan view of the sight shown in Fig. 1;

Fig. 3 is a side elevational view of the sight shown in Fig. 2;

Fig. 4 is a cross-sectional view taken along line 4—4 of Fig. 3;

Fig. 5 is a longitudinal sectional view taken along line 5—5 of Fig. 3;

Fig. 6 is a cross-sectional view taken along line 6—6 of Fig. 3; and

Fig. 7 is a view similar to Fig. 1 but with a detachable part of the sight removed.

Referring now to the drawings, in which I have illustrated my invention by showing a preferred embodiment of the same, the reference numeral 10 indicates, in general, a bolt action rifle having a receiver 11, the bridge 12 of which, in this instance, is provided with a transverse dove-tail 55

slot 13, in the upper face thereof. In the preferred form of the invention shown herein I take advantage of this dove-tail slot to support the improved sight, generally designated by the reference numeral 14, on the rifle 10.

The sight 14 includes, a supplemental base 15, having, at the forward end thereof, a dove-tail 16, adapted to be received in the dove-tail slot 13, of the receiver, the supplemental base at its rear end extending laterally outwardly and downwardly at 17, to provide for the connection of the supplemental base 15 to base 18, by extension 19.

The extension 19 is of a length to space the base 18, which carries the aperture 20 of the sight 15 in a manner to be hereinafter described, at such a distance rearwardly of the receiver 12 as to bring the aperture closely adjacent the comb 21 of the rifle. In the particular instance shown, the extension 19, at least through part of its length, as at 22, is of cylindrical rod-like shape and for convenience of manufacture, is of uniform diameter from end to end and mounted in or rigidly attached to base 18, the rod-like part of the extension extending forwardly from the base 18, in a direction parallel to the axis of the rifle barrel, to be detachably secured in an opening 23, in the supplemental base 15.

In order that the aperture 20 may be adjusted longitudinally of the rifle, into a position suitable for the needs of an individual shooter, the opening 23, in the instance shown, extends entirely through the part 17 of supplemental base 15, the cylindrical part 22 being movable axially of opening 23 and held against movement, when in adjusted position, by a clamping plate 24, mounted in the vertical outwardly facing slot 25, in supplemental base 15, the plate 24 being forced against the extension by means of a clamp screw 26, extending through the plate 24 and threaded in part 17, of supplemental base 15. In order to control rotational movement of the cylindrical part 22, of the extension, in the opening 23, of supplemental base 15, the cylindrical part 22 is flattened through at least part of its length, as at 27, the flattened portion 27 being engaged by the upper end of plate 24.

It will be readily understood without further description that by loosening the clamping screw 26, and thus the clamping plate 24, the cylindrical part 22, of the extension, may be freely withdrawn from or inserted into the opening in the supplemental base 15 and adjusted back and forth therein. When inserted or adjusted in opening 23, to a point effecting a desired position of the aperture 20, the clamp screw 26 may be tightened to hold the extension, and thus the base 18, against further movement. The cylindrical portion of the extension closely fits the opening 23 and the flattened portion 27 is parallel to the axis of this cylindrical portion, so that after adjustment of the latter, backwards or forwards in opening 23, the engagement of plate 24, with the portion 27, will effect rotation of the extension to bring the flattened portion 27 into a substantially vertical position, and thus the aperture into normal sighting position.

For the purpose of locking the supplemental base 15 and the extension element 19 against relative movement, as well as to form a convenient means for insuring that these parts may be returned to any position of adjustment after the extension element is separated from the supplemental base 15, a series of equally spaced vertical slots 28 are cut into the face 27, of extension element 19, the upper end of the plate 24 having

spaced ribs 29 adapted to enter the slots 28. As the slots and ribs have the same center to center spacing it will be apparent that the ribs may enter the slots at any portion of element 19 at the flattened portion 27 thereof. The plate 24, at its lower end, is provided with a longitudinally directed rib or toe 30 bearing against the supplemental base 15 at the lower end of slot 25, the plate swinging on the toe 30, as the clamp screw 26 is tightened, to cause the ribs 29 to enter the slots 28 to lock the extension element against rotation and movement in the direction of its axis. Preferably the sides of each rib 29 are tapered towards one another towards their outer edges, the slots 28 having a similar taper so that engagement of the plate 24 and extension element 19 is limited to the sides of the ribs and slots.

It is common practice in receiver sights to mount the aperture on a vertically movable slide, the latter being adjusted in a vertical direction by a screw, mounted on the slide and engaging a threaded nut carried on the base. As the aperture, in most instances, interferes with the use of a telescope sight, it is common practice to mount the nut, in the base, so that the threads thereof may be disengaged from the adjusting screw to permit free withdrawal of the slide from the base. During the normal use of the screw for adjusting purposes the nut is pressed against the threads of the screw by a spring. In the present instance, owing to the detachable connection of the extension element with the base 17, I am able to dispense with the use of a movable nut and the elevation and windage adjustments may be kept at proper setting at all times.

In the form of the invention shown in the drawings the aperture disc 20 is supported in usual manner for transverse movement on the horizontal arm 31, of slide 32, the latter being of inverted L-shape and having a vertical arm 33, supported on base 18, for movement in a vertical direction, arms 31 and 33 being at right angles to one another with arm 33 vertically and arm 31 horizontally disposed. The arm 33 is of dove-tail cross-sectional shape and supported in an outwardly facing vertical slot 34, in base 18, the base 18 at one of the side edges of the slot 34 fitting the adjacent dove-tail edge of the arm 33 and at the other side edge, of the slot 34, tapering outwardly to receive the adjacent face of clamping plate or wedge 35, the latter being mounted between the slide arm 33 and the base 18 at the edge of the slot 34.

Vertical adjustment of slide 32 is brought about by vertical adjusting screw 36, having a stem 37, mounted for rotation in arm 31 and having a lower threaded end 38, received in a vertical threaded opening 39, of base 18, the opening 39 being preferably threaded its entire length. Axial movement of screw 36, in arm 31 in one direction is prevented by the engagement of shoulder 40, on screw 36, with the under side of arm 31, movement in the opposite direction being prevented by the engagement of finger piece or screw head 41, mounted on the upper end of stem 37, with the upper face of arm 31.

A click spring 42, of usual form, mounted in a recess in the upper face of arm 31, engages the lower end of screw head 41, to control the rotational movement of the head 41, and thus screw 36, in well known manner. In order that there may be no lost motion, between the screw 36, slide 32, and base 18, during the rotation of screw 36, and so that small movements of rota- 75

tion of screw 36 may be reflected in corresponding movements of the slide, the base 18 is bored or drilled at 43, to receive a shoe 44, which is pressed against the screw 36, by a screw 45, threaded 5 in opening 43, the shoe pressing the screw into tight engagement with the threads of opening 39. The upper end of head 41 is counterbored to receive a screw 46, threaded in stem 37 and drawing the head 41 downwardly on the stem 37 10 until the lower end of the head engages the upper face of arm 31, the shoulder 40 at this time being in engagement with the under face of arm 31, screw 46, threaded in head 41, engaging the stem 37 to hold the head thereon against movement with respect to the stem. 15

The typical rifle, shown in Figs. 1 and 7, is provided with a receiver 11, in which a longitudinally movable bolt 48 is mounted, the latter having a bolt head 49 and cocking piece 50 which 20 extend a considerable distance rearwardly of the receiver 12. The supplemental base 15 is mounted on the receiver 12 in the position normally occupied by the usual receiver sight. It will be noted that a sight so positioned is at a considerable distance from the comb 21 and that in any event it would be impossible to bring the eye of the shooter very close to the sight as it is necessary to avoid contact with the cocking piece 50. In the present instance the extension 22 brings 25 the sight into a position rearwardly of the receiver 11 such that the aperture 20 is closely adjacent the comb 21 or at least rearwardly of the cocking piece 50 to a sufficient extent so that the shooter may bring his eye close to the aperture. 30

Elevation and windage or lateral adjustments of the sight are brought about by rotation of screws 36 and 51 in well known manner and it will be apparent that as the axis of extension 40 22 is parallel to the axis of the rifle barrel the sight base 18 may be adjusted longitudinally of the rifle without effecting the sight adjustment in any material way. The ribs 29 of the clamping plate 24 and the grooves 28 of the extension 45 22 co-operate to lock the extension against longitudinal as well as rotational movement and serve as guides to the shooter in restoring the sight to

original adjustment after the base 18 and extension 22 have been separated from supplemental base 15. In order to lock the slide 32 against movement the wedge 35 may be pressed against the slide arm 33 by clamp screw 52. 5

While I have shown and described a preferred form of the invention, it will be readily understood that it is not to be limited to the details shown, but is capable of modification and variation within the spirit of the invention and the scope of the appended claims. 10

What I claim is:

1. In a receiver sight for a rifle, a sight carrying base, a supplemental base adapted to be attached to the rifle, an extension rigidly connected 15 to the sight carrying base and extending towards and having its outer end mounted in said supplemental base, said end being generally cylindrical and said supplemental base having a cylindrical opening parallel to the axis of the rifle barrel 20 open at one side, a clamping plate on the supplemental base, said plate and extension end having co-operating ribs and grooves, and means for clamping said plate in said open side against the extension end with said ribs and grooves inter- 25 engaging to restrain longitudinal movement of the extension in the cylindrical opening.

2. In a receiver sight for a rifle, a supplemental base adapted to be attached to the receiver of a rifle and having a cylindrical opening therein 30 the axis of which is parallel to the axis of the rifle barrel open at one side, a sight carrying base, an extension rigidly attached to the sight carrying base and extending longitudinally towards the supplemental base, said extension at least at its outer end being cylindrical and received in the cylindrical opening of the supplemental base, there being a flat vertical face on the extension end and a series of spaced vertical outwardly facing grooves cut into the extension 40 end through said face, a clamping plate mounted on said supplemental base, a series of spaced ribs on said plate received in the grooves of the extension end, and means for urging the plate in said open side against the extension end. 45

FREDERICK A. KUHN.
